UNITED STATES PATENT OFFICE

ROSSITER S. SCOTT, OF NEW YORK, N. Y.

CONVERTIBLE GARTER AND HOLDING DEVICE

Application filed July 7, 1928. Serial No. 291,009.

This invention is primarily a convertible garter, adapted to be used in one adjustment for supporting socks and in another adjustment for holding stockings in place, but 5 embodies also a holding device capable of other uses. An example of convertible garter is shown in my Patent 1,588,625 granted June 15, 1926. The special utility and object of the present invention is to enable a 10 man to change from socks, for example to golf stockings, without requiring separate garters for the two uses. Further objects are to improve the construction, efficiency and comfort of garters of the class referred 15 to, with pivoting movements between the several components, thus affording self conformation to the wearer and maximum comfort. Other and further objects and advantages will be explained in the following description of an illustrative embodiment or 20 will be apparent to those skilled in the subject.

To the attainment of such objects and advantages the present invention consists in 25 the novel garter and the novel features of arrangement, combination, construction and operation herein illustrated or described.

In the accompanying drawings Fig. 1 is a perspective view of a convertible garter 30 embodying the present invention, with the several connections disconnected.

Fig. 2 is a substantially central vertical section with the parts adjusted to closed or holding position.

Fig. 3 is an enlarged vertical section of a 35 detail.

Fig. 4 is a section on the line 4—4 of Fig. 3. As shown in Fig. 1 the circular band 10 is of the wide type, preferably elastic, and 40 attachable through the use of a stud and socket fastening, which may be of various forms. Thus near one end of the band 10 is shown a recessed clasp plate 11 formed with a socket or recess 12, the wide elastic band 45 extending through the plate 11, in a manner disclosed and claimed in my copending application Serial No. 266,814, filed March 31, 1928, the band extending beyond the plate in the form of a free end 13.

The other end of the wide band 10 has

attached to it a member 15, preferably composed of leather, which may be termed a pad, and is stitched to the band by appropriate stitching, as shown.

The stud member 16 of the detachable fastening is shown as extending through a suitable aperture in the pad 15, and adapted to be engaged by the tapered recess or socket 12 in the clasp plate 11.

In the convertible type of garter it is necessary to provide detachable connections between the two ends of the band 10 which encircles the leg and the top end of the strap which extends between the band and the sock. In accordance with the illustrated embodiment of this invention the stud and socket already described constitute on detachable connecting means, the other consisting of a hanger 17 mounted on the strap and with which hanger the band is readily connectible and disconnectible. The arrangement could be reversed.

The hanger 17 is of a special character adapted to cooperate with the headed stud 16. Thus the narrow end 18 of the hanger is formed with a longitudinal slot or recess as wide as the head of the stud so that the stud can be inserted in the slot adjacent to its top end. In connection with this arrangement there is shown an elastic member or buffer 19 mounted in the slot in a manner to engage yieldingly with the slot. The buffer 19 may consist of a bar or block of rubber secured or clamped by a cross strip or loop 20 in a position so near to the end of the slot as to accommodate the stud shank, but not its head. The strip may consist of metal crimped into place as shown in Fig. 4 so as to hold tightly the buffer in its proper position. The action in inserting or removing the stud is well shown in Fig. 3 where the hanger 17 is being forced into engagement with the stud, the stud deflecting the upper end of the buffer 19 which yields to permit the engagement until, when the stud reaches the dotted line position, the buffer returns to normal and so holds the parts yieldingly connected.

An additional advantage of the described arrangement is that the buffer and its clamp-

ing strip may be adjustably slid along the narrow end of the hanger as will be clear from the illustration in Fig. 1. The side bars of the hanger at this point may be circular in cross section and the buffer and the clamp may be adjusted within limits, as shown, being held frictionally in their set position. This permits the taking up of wear in case the rubber buffer should wear down.

5 Preferably the stud 16 is mounted on one end of the garter band 10 while the hanger 17 has attached to its wide end 21 a fabric strap 22 which may extend from the hanger downwardly to the sock. The lower end of 10 the strap is provided with a button 23 engageable by a loop 24 to hold the sock, this loop being suspended from a doubled portion or 15 strip 25 constituting part of the strap.

When the hanger 17 is applied to the stud 20 16 the garter is readily adapted to the sustaining of socks, whereas by detaching the hanger from the stud the garter is readily available for sustaining golf stockings or the like. When changing from sock to golf 25 stockings the wearer is not required to detach the garters from the socks but merely to disengage the sock straps and hangers from the studs. Thus the straps are not likely to become lost, while the wide elastic 30 band garter is highly suitable for sustaining golf or other stockings.

It will thus be seen that there has been described a garter embodying the principles and attaining the advantages of the present 35 invention. Since various matters of arrangement, combination, construction and operation may be modified without departing from the principles involved it is not intended to limit the invention to such matters except 40 so far as set forth in the appended claims.

What is claimed is:

1. A convertible garter comprising a band for encircling the leg, a connecting strap to extend between the band and a sock, and 45 means detachably connecting the strap and one end of the band, comprising a headed stud on one of them and a hanger on the other, the hanger having a slot of width to receive the stud head and an elastic member or buffer 50 mounted in the slot.

2. A convertible garter comprising a band for encircling the leg, a connecting strap to extend between the band and a sock, a headed stud on one band end, means detachably connecting the other band end thereto, and a hanger on said strap with which said stud is 55 readily connectible and disconnectible, consisting of a recessed piece with elastic member in its recess to engage yieldingly the said 60 stud.

3. A garter as in claim 2 and wherein the hanger consists of a plate with recess slot wide enough to admit the stud head, and the elastic member is a buffer clamped in the slot 65 in position to yield to permit the stud head

to be inserted and to hold the stud when engaged.

In testimony whereof, I have affixed my signature hereto.

ROSSITER S. SCOTT.
